COMBINED PLAYGROUND CLIMBER AND SLIDE

Robert S. Wormser, Hillsdale, Mich., assignor to Game-Time, Inc., Litchfield, Mich., a corporation of Michigan

Filed Apr. 1, 1968, Ser. No. 11,238

Term of patent 14 years

Int. Cl. D21—03

U.S. Cl. D34—5

FIG. 2

FIG. 4

FIG. 3

FIG. 1 is an elevational view of the right side of combined playground climber and slide in accord with my new design, the left side being identical thereto in appearance,

FIG. 2 is a front elevational view,

FIG. 3 is a rear elevational view, and

FIG. 4 is a top plan view.

The characteristic feature of my design resides in the combination of the slide and the central column extending through and above the platform and the outer columns extending over the platform and attached at the top of said central column, all as shown.

I claim:

The ornamental design for combined playground climber and slide, substantially as shown and described.
